UNITED STATES PATENT OFFICE.

ERASTUS E. WINKLEY, OF LYNN, MASSACHUSETTS.

SEWING-MACHINE.

1,197,988.

Specification of Letters Patent. Patented Sept. 12, 1916.

Application filed October 30, 1912. Serial No. 728,623.

To all whom it may concern:

Be it known that I, ERASTUS E. WINKLEY, a citizen of the United States, residing at Lynn, in the county of Essex and State of Massachusetts, have invented certain new and useful Improvements in Sewing-Machines; and I do hereby declare the following to be a full, clear, and exact description of the invention, such as will enable others skilled in the art to which it appertains to make and use the same.

The present invention relates to sewing machines, and more particularly to chain stitch shoe sewing machines of the class which employ a curved hook needle, and which are used in sewing the inseams of boots and shoes.

During each cycle of stitch forming operations of machines of this class, starting with the needle in retracted position with a loop of thread held in its hook, the needle advances through the loop last formed, and through the materials into position to receive the thread from the looper. The looper then lays the thread in the hook of the needle, after which the needle retracts, drawing a new loop of thread through the materials and through the previously formed loop. In order to enable the shoe to be removed when the seam has been completed, and another shoe to be placed in the machine in position to be sewed, it is necessary that the needle be brought to rest in retracted position out of engagement with the work. When the needle is retracted out of engagement with the work during a cycle of stitch forming operations, the last loop drawn out is held in the hook of the needle, and it has usually been necessary in machines heretofore devised to manipulate either the machine or the shoe in order to free the thread from the barb of the needle. Machines have been constructed in which the direction of movement of the main driving shaft of the machine has been automatically reversed upon stopping the machine to free the thread from the needle and bring the needle to rest out of engagement with the work.

The primary object of the present invention is to produce a curved hook needle inseam shoe sewing machine provided with means whereby, without reversing the direction of movement of the main driving shaft of the machine, the thread and parts of the machine may be placed in such condi-

tion as to offer no obstacle to the removal of the shoe, or to the insertion of another shoe in the machine in position to be sewed. With this object in view the invention contemplates the provision in a machine of this class of means to free the last needle loop from the stitch forming devices during the forward rotation of the main shaft of the machine and bring the needle to rest out of engagement with the work. In the preferred embodiment of the invention the above object is accomplished by the provision of means to render the looper inactive during a forward cycle of movement of the machine, and thereafter to cause the needle to come to rest out of engagement with the work. Since the looper is rendered inactive during a normal cycle of movement of the needle, the needle is rendered free of thread when it is brought out of engagement with the work so that the shoe can be readily removed. In the best form of the invention which has yet been devised, mechanism is provided which acts automatically when brought into action and is timed and controlled with relation to the other parts of the machine so as to throw the looper out of action during a cycle of movement of the machine before the needle is looped, and thereafter during the same cycle of movement to bring the needle to rest out of engagement with the work.

Another feature of the invention consists in the provision of mechanism for interrupting the feeding action of the feeding devices of the machine during the rotation of the main shaft. This mechanism is timed with relation to the other parts of the machine so that the feeding action of the feeding devices is interrupted when the needle is brought to rest out of engagement with the work thereby preventing the feeding devices from feeding the shoe forward after the seam is completed and the needle brought to rest. Upon starting the machine the feeding devices are restored to action in timed relation to the needle and other parts of the machine by mechanism which is so timed that the feeding action of the feeding devices is suspended until the needle has advanced and retracted in the first cycle of stitch forming operations and the feeding of the shoe before the needle advances through the work is prevented.

A further feature of the invention consists in the provision of mechanism acting

during the forward rotation of the shaft for releasing the tension on the thread. This mechanism is timed with relation to the means for causing the needle to come to rest 5 out of engagement with the work so that the tension is released as the needle is brought to rest.

Further features of the invention consist 10 of certain constructions, arrangements and combinations of parts, the advantages of which will be obvious to one skilled in the art from the following description.

The various features of the invention will 15 be readily understood from an inspection of the accompanying drawings and the following detailed description.

In the drawings, Figure 1 is a sectional elevation of the machine looking from the left, showing the parts in the position which 20 they occupy during the operation of the machine in sewing a seam; Fig. 2 is a side elevation of the machine looking from the right, showing the parts in the positions they assume when they have been placed in 25 condition to permit the removal of the shoe; Fig. 3 is a rear elevation of the machine with the parts in the same positions as in Fig. 2; Fig. 4 is a detail side elevation illustrating particularly the mechanism for releasing the tension and the mechanism for 30 unlocking the back gage and welt guide and for holding the welt guide in retracted position, with the parts in the same positions as in Fig. 2; Fig. 5 is a side elevation of the 35 driving mechanism located in the base of the machine with a portion of the casing broken away to show the interior structure; Fig. 6 is a detail horizontal sectional view illustrating a portion of the mechanism at 40 the rear of the main shaft of the machine; Fig. 7 is a section taken on the line 7—7 of Fig. 1, looking in the direction of the arrows; Fig. 8 is a detail elevation of the 45 mechanism for actuating the needle and a portion of the mechanism for disconnecting 50 the needle from its actuating mechanism, showing the parts in running positions; Fig. 9 is a section taken on the line 9—9 of Fig. 8; Fig. 10 is a detail sectional view 55 taken on the line 10—10 of Fig. 2; Fig. 11 is a detail side elevation illustrating particularly a portion of the mechanism for throwing the looper, feed mechanism and 60 needle out of action upon stopping the machine and for throwing these devices into 65 action when the machine is started; Fig. 12 is a diagrammatic view showing a development of the surface of the grooved roll which forms a part of the mechanism for throwing the looper, feed mechanism and 70 needle into and out of action; Fig. 13 is a diagrammatic view of the cams for disconnecting the needle, looper and feed slide from and for connecting them with their 75 actuating mechanisms; Fig. 14 is a side ele-

vation of the stopping cam disk; Fig. 15 is a side elevation of the starting cam disk; and Fig. 16 is a detail side elevation illustrating particularly a portion of the mechanism for releasing the tension on the 70 thread upon stopping the machine and for restoring the tension to the thread when the machine is started.

In the drawings the invention is illustrated as embodied in a welt and turn shoe 75 sewing machine such as that shown and described in the application of Andrew Eppeler, Serial No. 447,542, filed August 8, 1908. The machine is provided with a curved hook needle 1, a looper 2, a thread finger 3, a welt guide 4, a back rest 5, a feed point 6 and a channel guide 7, which devices are operated through suitable connections by cams carried by the main shaft 8 of the machine. As usual in this type of machines, 80 the main shaft makes one revolution for each cycle of operations performed by the stitch forming and work feeding devices.

During the sewing operation the machine 85 is driven through a belt pulley 9 secured to the end of the main shaft and connected by a driving belt with a pulley 10 mounted in the base of the machine. The pulley 10 is connected through bevel gears 11 with a sleeve 12 mounted on the driving shaft 13 90 and carrying one member 14 of the driving clutch. The driving shaft carries the other member 15 of the clutch, and also carries the driving pulley 16 through which motion is imparted to the driving shaft 13 from 95 the power shaft. The engagement of the members of the driving clutch is controlled through a treadle 17 connected with the clutch operating wedge 18. In the construction illustrated the treadle is constructed of 100 two parts which are arranged for independent movement. Of these the part 19 is pivoted upon a shaft 20 carried by suitable brackets on the frame, and is connected by means of a link 21 with an 105 arm 22 extending down from the clutch operating wedge 18. A block 23 is secured to or formed integral with the arm 22 and an adjustable stop bolt 24 threaded into the block and arranged to engage a point on 110 the frame serves to limit the upward movement of the part 19 of the treadle. The part 19 is yieldingly held up by a heavy coiled spring 26 connected at one end there- 115 to, and at the other end to a fixed part of the machine frame. The other part 27 of the treadle is pivoted at the upper end of an arm 28 on the part 19, so that it is permitted to move independently of the part 19. The part 27 of the treadle is connected 120 by means of a link 29 with a bell crank lever 30 pivoted at 31 and provided with a forwardly extending arm to which is attached the lower end of a rod 32. A coiled spring 33 surrounding this rod is inter- 125

posed between a collar 34 on the rod and a lug 35 on the frame of the machine, through which the rod 32 passes. The rod 32 is connected with and arranged to control the 5 mechanism for throwing the looper, needle and feed slide out of action, as will be hereinafter described.

The needle 1 is secured in the usual manner to the needle segment 36 pivotally 10 mounted on a stationary portion of the machine frame, and connected by a link 37 with a cam actuated lever 38. To permit the needle actuating mechanism to be disconnected from the needle so that the needle 15 may be brought to rest during the rotation of the main shaft of the machine, the lever 38 is made up of two parts 39 and 40, as shown particularly in Fig. 8. The part 39 of said lever is pivoted on the shaft 41, and 20 carries a cam roll 42 which engages a cam on the main shaft of the machine. The part 40 of the needle lever is also journaled upon the shaft 41, and a slide 43 is connected with the part 40 of said lever. This slide 25 is formed with a yoke which embraces the hub of the part 39, and with a narrow forward portion which slides between flanges 44 on the part 40. This slide is held from lateral movement with relation to the part 30 40 of the lever by a screw 45 secured to the slide and operating in a slot in the part 40. During the normal operation of the machine the slide 43 occupies the position illustrated 35 in Fig. 8, with the forward extremity thereof located between inwardly projecting lugs 46 on the part 39 of the lever. When the slide is in this position the parts 39 and 40 of the lever are locked together so that they oscillate in unison, thereby imparting the 40 proper oscillatory movements to the needle during each cycle of operations of the machine. When the slide 43 is moved to the rear with relation to the part 40 of the needle actuating lever, the forward end of 45 the slide is withdrawn from between the lugs 46 on the part 39 and thereafter the part 40 of the lever connected with the needle remains at rest, and the part 39 oscillates idly. In order to withdraw the 50 slide 43 to disconnect the parts of the needle actuating lever, a lever 47 pivoted on a shaft 48 is connected by means of a link 49 with the rear end of the slide 43. A cam roll 50 is carried by the lever 47 and engages a cam groove 51 in a cam lever 53 mounted on the shaft 41. When the cam lever 53 is moved upwardly from the position in which it is illustrated in Fig. 8, the slide 43 is moved rearwardly to withdraw 55 the forward end thereof from between the lugs 46. In order to hold the part 40 of the needle actuating lever from displacement when the slide 43 is withdrawn, an arm 55 on the frame extends downwardly adjacent 60 to the rear end of the slide, and when the 65

slide is withdrawn the lower extremity of said arm engages a face 56^x formed on the rear portion of the slide. When the slide 43 has been withdrawn to disconnect the parts of the needle actuating lever, and the 70 cam lever 53 is moved downwardly, the slide will be moved forwardly to project the forward end thereof between the lugs 46 on the part 39, thereby again connecting the two parts of the lever. Mechanism is provided 75 for actuating the cam lever 53 to retract the slide 43 and thereby bring the needle to rest upon stopping the machine and said mechanism is constructed and arranged and timed with relation to the rotation of the main 80 shaft of the machine so that the needle is disconnected from its actuating mechanism and brought to rest at that point in a forward cycle of movement of the machine when the needle has reached a retracted position out of engagement with the work. When the machine is started, the cam lever 53 is actuated to connect the needle with its 85 actuating mechanism at the same point in the rotation of the main driving shaft and 90 in a cycle of movement of the machine at which it was disconnected.

The upper portion of the cam groove 51 is constructed in the form of the curve of the arc of a circle, the center of which lies 95 in the axis 41 of the lever 53, as shown in Fig. 8 and Fig. 13, in which this groove is represented in dotted lines. The slide 43 will therefore be actuated to throw the needle out of action during the last portion 100 of the upward movement of the lever 53 from the position in which it is shown in Fig. 8, and when the lever 53 is actuated to connect the needle with its actuating mechanism, the slide 43 will be actuated to throw 105 the needle into operation during the initial part of the downward movement of the lever 53.

As above stated the needle is brought to rest out of engagement with the work during the forward rotation of the shaft and during a forward cycle of movement of the machine, and mechanism is provided for rendering the looper inactive during the last 110 cycle of movement of the needle, so that the needle is retracted while its hook is empty and is free of thread when brought to rest out of engagement with the work. In the construction illustrated, the looper is provided with a shank which is received in a 115 cylindrical socket in the lower end of an arm 56, the connection between the looper shank and the arm being such that the looper can be adjusted vertically. The shank of the looper is held in the arm by means of a 120 clamping screw 57. The arm 56 is pivoted midway its length to a block 58 secured to the forward end of a cam actuated slide 59. The slide 59 is arranged above the needle 125 and in a plane parallel with the plane of the 130

needle, so that the reciprocating movements of the slide impart forward and rearward movements to the looper. The movements of the looper at right angles to the plane of the needle are produced by oscillating the arm 56, the movements of the looper due to the reciprocation of the slide and the oscillation of the arm acting to carry the thread around the needle and lay it in the barb. 5 The upper end of the arm 56 is provided with a socket in which a rod 59^a is received. This rod is provided at its upper end with a socket or bearing which receives a rod 60 secured to an arm 61 loosely mounted upon 10 a rock shaft 62 and arranged to slide longitudinally of said shaft. An arm 63 is secured to the forward end of the rock shaft 62, and is provided with a pin 64 which is adapted to engage a hole in the arm 61, and thereby lock the arm 61 and the arm 63 together, so that they oscillate in unison. 15 When the arm 61 is moved to the rear, the pin 64 is disengaged from the perforation in said arm, and the arm 63 then oscillates idly. 20 The rod 59^a is free to slide in a socket in the arm 56, and the rod 60 is free to slide in the socket in the upper end of the rod 59^a. The shaft 62 is provided with a downwardly projecting arm 65 at its rear end which is provided with a roll engaging a cam on the main shaft of the machine. In order to render the looper inactive during the last forward movement of the needle before it is brought to rest, mechanism is provided for 25 moving the arm 61 to the rear to disconnect said arm from the arm 63 of the rock shaft. To this end a bell crank lever 66 is pivoted at 67 on the frame of the machine and one arm 68 of said bell crank lever carries a roll 30 69 which engages a groove in the hub of the arm 61. The other arm 70 of said bell crank is connected by means of a link 71 with a lever 72 (Fig. 4) journaled on the shaft 48. The lever 72 carries a cam roll 73 which is 35 arranged to engage a cam groove 74 formed in the cam lever 53. The shape of the cam groove 74 is such that when the cam lever 53 is moved upwardly from the position shown in Fig. 1, the lever 72, link 71, and bell crank 40 66 will be actuated in a direction to disconnect the arm 61 from the arm 63 of the rock shaft. To prevent the displacement of the parts of the looper mechanism when the arm 61 is disconnected from the arm 63, a pin 61^a 45 is mounted on the hub of the arm 61 and is arranged to enter a slot 62^a in a bracket 63^a secured to the frame, when the arm 61 is moved rearwardly to disengage the pin 64 from the hole in the arm 61. 50 The lower portion of the cam groove 74 has the form of the curve of the arc of a circle, as shown in Fig. 13, in which the cam groove 74 is diagrammatically illustrated in heavy full lines. The center of the curve of 55 this portion of the cam groove 74 lies in the

axis of the lever 53, so that the lever 72 is actuated to disconnect the looper from its actuating mechanism during the initial part of the upward movement of the lever 53. When the lever 53 is moved downwardly to 70 connect the looper with its actuating mechanism the lever 72 is actuated to throw the looper into operation during the final downward movement of the lever 53. The lever 53 is actuated in timed relation to the rotation of the main shaft and to the movements of the needle to disconnect the looper from its actuating mechanism during a cycle of movement of the machine before the needle is looped so that the needle is free of thread 75 when it retracts out of engagement with the work. 80

To prevent the feeding devices of the machine from continuing to feed the shoe forward after the needle is brought to rest out of engagement with the work, the machine is provided with mechanism for interrupting the feeding action of the feeding devices. The feeding devices of the machine comprise a feed slide upon which the feed point and channel guide are supported, the feed point and channel guide being mounted for oscillatory movement on the slide and arranged to move laterally with the slide in the usual manner. The feed slide of the machine 90 illustrated in the drawings is of the usual construction. The cam actuated lever for imparting forward and rearward movements to the feed slide is indicated at 75. This lever is provided with a hub 76 pivoted at 77 on the machine frame, the usual adjustable connection, indicated at 78, being provided between the lever and the hub. The lever is provided intermediate its ends with a slot within which is adjustably secured a block from which projects a pin 79 having mounted thereon a block engaging a slot in the feed slide. This connection between the lever and feed slide is of usual construction, and permits an adjustment of 95 the length of feed. In order to permit the lateral movements of the feed slide to be interrupted during the continued rotation of the main shaft of the machine, the lever 100 105 110 115 120 125 130 135 140 145 150 155 the feeding devices thereby interrupted. In order to actuate the member 81 of the feed slide lever to throw the cam roll 82 into and out of engagement with the cam groove, a lever 86 is pivoted on the shaft 41 and is provided at its forward extremity with a slot which engages a pin 88 carried by the member 81. A second arm 89 on the lever 86 extends upwardly between the arms of a yoke 90 also journaled on the shaft 41, the arms of the yoke being connected with the arm 89 by means of a pin 91. The upper end of the yoke 90 is connected by means of a universal joint with a cylinder 92 in which 10 operates a rod 93 connected by means of a universal joint with a lever 94 journaled upon the shaft 48. A coiled spring 95 surrounds the rod 93, and engages at one extremity a head 95^a on the rod, and at the other a cap 95^b mounted on the end of the cylinder. It will be noted that by means of this connection between the yoke 90 and the lever 94 the yoke will be actuated positively by the lever when the lever is moved forward, but when the lever is moved rearwardly the spring will yield, in case any obstruction prevents the rearward movement of the yoke. The lever 94 carries a cam roll 96 which engages a cam groove 97 formed in the cam lever 53. The shape of the cam groove 97 is such that when the cam lever 53 is moved upwardly from the position in which it is shown in Fig. 1, the lever 94 will be moved forwardly, thereby actuating the yoke 90 and lever 86 in a direction to withdraw the cam roll 82 from the cam groove 82^a and throw the feed slide out of action. The member 81 of the feed slide actuating lever is provided with a downwardly extending lug 98 which is arranged to rest between fixed lugs 99 when the member 81 is actuated to withdraw the cam roll 82 from the cam groove, thereby preventing any lateral movement of the lever 75 and the feed slide until the feed slide is again thrown into action. When the cam lever 53 is moved downward from the position in which it is shown in Fig. 2, the lever 94 will be moved to the rear, thereby tending 40 to actuate the yoke 90 in a direction to lift the horizontal arm of the lever 86 and engage the cam roll 82 with the cam groove to throw the feed slide into operation. The spring connection between the lever 94 and the yoke 90, permits the lever 94 when it is moved rearwardly, to move independently of said yoke in case the cam groove 82^a is not in position to receive the roll 82 when the lever 94 is actuated. The cam roll 82 is thereby held in yielding engagement with the exterior of the cam disk, and when the cam groove arrives in position to receive the roll, the roll will be lifted into engagement with the cam groove by the action of 50 the spring 95.

In order to insure that the cam roll 82 will engage the cam groove when said cam groove arrives in position to receive the roll, positive means is provided for causing the cam roll to engage the cam groove. To this 70 end the yoke 90 is provided with a roll 100 arranged to be engaged by a projection 101 on the cam disk when the cam groove 82^a arrives in a position to receive the roll 82. The yoke 90 is thereby moved to the right about 75 the shaft 41, and the cam roll 82 is actuated positively to throw it into engagement with the cam groove. In order that the roll 100 may be out of the path of the projection 101 when the feed slide is thrown out and may 80 be thrown into the path of said projection when the feed slide is to be thrown into action, the yoke 90 is constructed so that the space between its arms is sufficient to permit the yoke to slide longitudinally of the shaft 85 41. The yoke is maintained in a position such that the roll 100 is out of the path of the projection 101 when the feed slide is inactive by the tension of the spring 102. When the lever 94 is actuated in a direction 90 to throw the feed slide into action the yoke 90 is moved inwardly along the shaft 41 by means of a forked cam arm 103 carried by an arm 104 on the lever 94 and arranged to engage a cam ring 105 on the shaft 41. During the normal operation of the machine the roll 100 is located beyond the path of the projection 101.

The cam lever 53 is actuated in timed relation to the rotation of the main shaft and 100 to the other parts of the machine so that the feed slide is out of action when the needle is brought to rest. In the present embodiment of the invention the feed slide is thrown out of connection with its actuating 105 devices when in retracted position ready to begin a work feeding stroke.

The cam groove 97 is constructed so that the end portions of the groove are substantially concentric with the axis of the lever 110 53 and the lever 94 is actuated to throw the feed slide out of and into action when the cam roll 96 is in an intermediate portion of the cam groove. The cam groove 97 is illustrated in comparatively light full lines in 115 Fig. 13.

It will be observed from an inspection of Fig. 13 that the relative forms and arrangement of the cam grooves 51, 74 and 97 are such that when the cam lever 53 is moved 120 upwardly the looper is first disconnected from its actuating mechanism, then the feed slide, and last the needle. When the cam lever 53 is moved in a reverse direction the cams on the cam lever will operate their respective mechanisms to throw the needle, looper and feed slide into action in an order reverse to that in which they were thrown out, that is, first, the needle, then the feed slide, and last, the looper.

In order that the looper may be rendered inactive during a forward cycle movement of the machine before the needle is looped, the feeding action of the feeding devices 5 interrupted and the needle brought to rest thereafter out of engagement with the work, mechanism is provided for actuating the cam lever 53 in timed relation to the rotation of the shaft and to the movements of 10 the parts of the machine to disconnect the looper, feed slide and needle from their respective actuating mechanism at the proper times in a cycle of movement of the machine. Mechanism is also provided to actuate the lever 53 to restore the needle, looper and feed slide to action in their proper timed relations when the machine is started. In the construction illustrated in the drawings, the mechanism for actuating the cam lever 53 comprises a stopping cam disk 106, a starting cam disk 107 fixed to the cam shaft 8, and a lever 108 provided with rolls 109 and 110 arranged to alternatively engage the stopping cam and the starting cam, said 20 lever being connected with the cam lever 53. The lever 108 is provided with a hub 109^a loosely journaled on the shaft 41, and an arm 110^a is formed on said hub, the end of which arm engages between projections 111 on an intermediate lever 112 also journaled on the shaft 41. This connection between the lever 108 and the lever 112 permits a relative longitudinal movement of said levers on the shaft 41, but causes the levers to 30 move in unison about said shaft. The lever 112 is provided with a rearwardly extending arm 113 (see Fig. 11), the end of which is arranged to engage between lugs 114 on the cam lever 53. An adjusting screw is threaded into each of said lugs, and these screws engage opposite sides of the arm 113, thereby providing an adjustable connection between the cam lever 53 and the lever 112. inspection of Fig. 13 that this movement of the cam lever 53 will throw the needle into operation. The second rise in the cam groove in the starting cam disk occurs at 5 the point indicated at 123, and referring again to Fig. 13 it will be seen that the movement of the lever 53 at this time will tend to throw the feeding devices into operation. The cam groove 82^a in the cam 10 disk carried by the cam shaft of the machine is not at this time in position to receive the cam roll 82 of the feeding devices, and the lever 94 at this time actuates the yoke 90 to engage the cam roll 82 with the 15 exterior of the cam disk, and the movement of the lever 94 after the roll 82 is brought into engagement with the surface of the cam disk causes a compression of the spring 95. The wedge 102, however, is at this time 20 actuated to move the yoke 90 inwardly to bring the roll 100 thereon into the path of the projection 101. The third rise in the cam groove in the starting cam occurs at 25 the point indicated at 124 and at the point in the rotation of the cam shaft when this rise engages the roll 110, the lever 108 is actuated to impart the final downward movement to the cam lever 53. This occurs when the pin 64 is opposite the hole in the 30 arm 61 and the arm 61 is advanced, engaging the pin with the hole in said arm, thereby throwing the looper into operation. At this point the needle has advanced through the materials in position to receive 35 the thread in its barb, and the looper is then thrown into action and operates to carry the thread about the needle. When the needle is retracted, carrying the loop of thread in its barb, the cam groove 82^a in the 40 cam disk has arrived in a position to receive the roll 82 and the roll is lifted into engagement with the cam groove by the action of the spring 95, or by the positive action of the projection 101 on the roll 100. 45 The parts of the machine are thus thrown into operation in their proper timed relations and continue to operate normally until the seam is completed and the lever 108 is actuated to disengage the roll 110 from the 50 groove in the starting cam disk and engage the roll 109 with the cam groove in the stopping cam disk.

In order to actuate the lever 108 to engage the rolls thereon alternatively with the 55 stopping cam upon the completion of the seam and with the starting cam to begin the sewing operation, a lever 125 is journaled upon the shaft 41 and is connected with the lever 108 by means of angular retaining 60 plates 126 secured to the hub of the lever 108 and engaging oppositely projecting lugs 127 on the hub of the lever 125. This connection between the lever 125 and the lever 108 causes said levers to move longitudinally of 65 the shaft 41 in unison, but permits the lever 125 to move angularly about the shaft independently of the lever 108. The lever 125 is constructed with forks which embrace the main shaft of the machine, the forks being provided respectively with inwardly projecting pins 128 and 129. It will be noted 70 from an inspection of Fig. 3 that the ends of the forks on the lever 125 are arranged out of line so that the pin 128 is located in position to engage a groove 130, while the pin 129 is opposite and in position to engage a groove 131 formed in a collar attached to the main shaft of the machine. The span of the forks on the lever 125 is such that when one of the pins 128 and 129 is in engagement with the corresponding groove the other pin is out of engagement with its corresponding groove. The formation of the grooves 130 and 131 will be understood 75 from an inspection of Fig. 12. Each of 80 said grooves comprises a portion running completely about the collar parallel with the direction of rotation of the shaft, a second portion also arranged parallel to the direction of rotation of the shaft and extending 85 partly about the collar and an angular cross-over between the parts of the groove. During the sewing operation the pin 128 is engaged with the lefthand portion of the cam groove 130, the lever 108 being thereby held 90 in position to maintain the roll 110 in engagement with the starting cam. When the seam has been completed, and it is desired 95 to place the parts of the machine in a condition to permit the removal of the shoe, the lever 125 is actuated to engage the pin 129 with the groove 131. The pin 129 at this time engages the lefthand portion of the groove 131, and when said pin arrives at the angular cross-over between the lefthand 100 portion of said groove and the right hand portion thereof, the lever 125 is moved to the right (Fig. 3), thereby shifting the lever 108 to the right to engage the cam roll 109 thereon with the cam groove in the stopping 105 cam disk. When the shoe has been removed and another shoe inserted in the machine, and it is desired to begin the sewing operation, the lever 125 is actuated to engage the pin 128 in the groove 130. The lever 125 is at this time in the position shown in Fig. 3, so that the pin 128 engages the righthand 110 portion of the groove 130. When the pin 128 arrives at the cross-over between the righthand portion of said groove and the 115 lefthand portion thereof, the lever 125 is moved to the left in Fig. 3, carrying the lever 108 to the left to engage the roll 110 with the cam groove in the starting cam disk, thereby starting the parts of the machine into action in their proper timed relations. 120

In order to actuate the lever 125, said lever is provided with an arm 135 in which is formed a slot to engage a pin 136 carried 125 130

by a lever 137 pivoted at 138^x and provided with a rearwardly extending arm connected with the rod 32.

When the treadle is released, the heavy 5 spring 26 lifts the treadle to disengage the members of the driving clutch. After the clutch members have been disengaged and the stop screw 24 engages the frame, the rod 32 is lifted by the action of the spring 33, 10 thereby actuating the lever 125 to engage the pin 129 with the groove 131. The main shaft continues to rotate under its own momentum after the members of the driving clutch are disengaged until the looper, feed 15 mechanism and needle are thrown out of action as described. When the treadle is depressed, the part 17 thereof is first moved about its pivot on the part 19, thereby depressing the rod 32 and actuating the lever 20 125 to engage the pin 128 with the groove 130. After the stop screw 27^a engages the part 19 of the treadle, the further depression of the treadle actuates the wedge 18 to engage the members of the driving clutch to 25 start the driving shaft of the machine.

It is to be observed that by means of the treadle mechanism employed, the pressure with which the members of the driving clutch are engaged, and thereby the speed 30 of the machine, may be varied without in any way affecting the mechanism for throwing the looper, feed slide and needle out of action. A catch lever 28^a is pivoted on the part 17 of the treadle and is provided with 35 a rearwardly extending hooked extremity which is arranged to hook over a lug 28^b on the part 19 to lock the parts of the treadle together when desired. The treadle may then be operated to engage and disengage 40 the members of the driving clutch without affecting the mechanism for throwing the looper, feed slide and needle out of action.

The space between the starting cam disk and the stopping cam disk is slightly greater 45 than the distance between the outer faces of the rolls 109 and 110 to prevent the rolls from engaging the cam grooves in the starting cam and stopping cam at the same time, which might cause breakage of the 50 parts of the machine. In order to support the lever 108 when said lever is moved laterally to disengage the roll 110 from the groove in the disk 107 and to engage the roll 109 with the groove in the disk 106, a 55 plate 138^a is secured to or formed on the starting cam disk 107 and a plate 139^a is secured to or formed on the disk 106, as shown in Figs. 14 and 15. These plates engage the rolls 110 and 109 when the lever 60 108 is moved laterally upon stopping the machine and prevent the displacement of the lever. The lever 108 is prevented from being displaced when it is moved laterally to disengage the roll 109 from the groove in 65 the stopping cam 106 and to engage the

roll 110 with the groove in the starting cam 107 upon starting the machine by a plate 140^a secured to or formed on the disk 106 and by a stop pin 141^a secured to the lever 108 which engages a portion of the frame. 70 It may happen that when the machine is started, the roll 110 will engage the portion 122 of the cam groove in the starting cam disk before the lever 108 has completed its lateral movement so that the roll 110 then 75 extends only part way into the groove in the starting cam disk. In order to support the roll 110 at the point 122 and prevent it from being thrown out of the cam groove, a plate 142^a is secured to the starting cam 80 disk 107. In case the operator depresses the treadle to start the machine and after the lever 108 is shifted to an intermediate position such that the rolls 110 and 109 are 85 out of engagement with the cam grooves in both cam disks, he releases the treadle, it may happen that the lever 108 will be displaced so that the roll 109 will be thrown out of position to engage the cam groove 90 in the stopping cam disk. In order to pick 95 up the roll 109 when the lever 108 becomes displaced in this manner and to throw the roll outwardly into registration with the outer portion of the groove in the stopping cam disk at the time that the cross-over in the groove 131 engages the pin 129, the plate 140^a is provided with an extension 143^a which extends inwardly to the central portion of the groove in the stopping cam disk. 100

The tension devices of the machine comprise a tension wheel 138 mounted on the shaft 139 journaled in the machine frame. A brake wheel 140 is attached to the other end of this shaft and a brake shoe 141 is 105 arranged to engage the brake wheel 140. The brake shoe 141 is pivotally mounted on the end of an arm 142 which is pivoted on a stud 143 secured to the machine frame. A lever 144 is also pivoted on the stud 143 110 and is connected at one extremity by a link 145 with an arm 146 secured to the shaft 48. The lever 144 is connected at its other extremity by a link 147 with a lever 148 pivoted at 149 on the machine frame. A 115 rod 150 is pivotally connected with the arm 142 and passes through a perforation in the end of the lever 148, and a coil spring 151 surrounding the rod engages the lever 148 and a nut 152 threaded on the rod. The 120 lever 144 and link 147 form a toggle which, during the sewing operation, is maintained in a straightened condition, as illustrated in Fig. 1, by the position of the arm 146, thereby causing the brake shoe 141 to be engaged 125 with the brake wheel 140 by the action of the spring 150. Upon stopping the machine at the completion of the seam, the shaft 48 is rotated to the left (Fig. 1), carrying the arm 146 into the position shown in Fig. 4. 13.

This movement of the arm 146 breaks the toggle 144-147 and causes the brake shoe 141 to disengage the brake wheel 140 and thereby release the tension on the thread. 5 When the machine is started, the shaft 48 is rotated to the right (Fig. 4) to restore the arm 146 and the toggle 144-147 to the position illustrated in Fig. 1, thereby restoring the tension to the thread. The 10 mechanism for actuating the shaft 48, as described, comprises an arm 153 secured to the shaft 48, a link 154 connected at one extremity by a universal joint with the arm 153 and at the other by a universal joint with the arm of the lever 155. The hub of the lever 155 is loosely mounted on the hub of the lever 108 but is confined between abutments on said lever so that the lever 155 is caused to move longitudinally of the 15 shaft 41 with the lever 108. A roll 156 is carried on the arm 157 of the lever 155 and when upon stopping the machine the lever 108 and lever 155 are moved to the right (Fig. 3), the roll 156 is moved into position 20 to be engaged by a cam 158 mounted on the inner face of the starting cam disk 107. By the engagement of the cam 158 with the roll 156 the lever 155 is moved to the left (Fig. 1) thereby, through the connections described, 25 rotating the shaft 48 to the left and actuating the arm 146 to release the tension. An adjustable stop screw 153^a threaded into an arm on the frame of the machine is arranged to engage the arm 153 and limit the 30 movement of said arm when the tension is released. A second roll 159 is carried by the arm 157 of the lever 155 and when said lever is moved to the left (Fig. 3) with the lever 108 upon starting the machine, the roll 159 35 is moved into position to be engaged by a cam 160 mounted on the cam disk 161 secured to the cam shaft of the machine. By the engagement of the cam 160 with the roll 159 the lever 155 is moved to the right 40 about the shaft 41, thereby rotating the shaft 48 to the right and actuating the arm 146 to restore the tension to the thread. 45 The welt guide 4 of the machine is connected by a link 162 with the welt guide 50 slide 163. The mechanism for advancing and retracting the slide is constructed substantially as shown and described in application Serial No. 447,542, referred to above, and comprises a spring 164 coiled about a 55 stud 165 and having an upwardly extending arm engaging a pin on the welt guide slide for advancing the slide and a cam actuated lever 166 connected by a link 167 with the clutch box 168 surrounding the slide and 60 provided with a clutch mechanism for retracting the slide. The work rest 5 is mounted on a slide 169 and is actuated by a coiled spring 170 as in said application. The mechanism for locking the welt guide 65 and work rest slides is of the usual construction.

tion and comprises clutch rolls 171 and 172 arranged to engage clutch surfaces on the welt guide and work rest slides, a wedge-shaped supporting member 173 arranged between the rolls and pivoted to the arm of a cam-actuated lever 174 by which the member 173 is actuated to unlock the slides and a spring 175 connected with the arm of said lever to actuate the member 173 to lock the slides. 75

slides. In order to maintain the welt guide and work rest slides unlocked when the needle is at rest, the lever 174 is provided with an arm 176 extending rearwardly over the shaft 48 and provided with an enlargement at its extremity which is arranged to be engaged by the end of an arm or member 177 loosely mounted on the shaft 48. During the normal operation of the machine the member 177 is held in forward position out of engagement with the arm 176 of the lever 174 by an arm 178 fixed to the shaft 48 and engaging a pin mounted on a member 177. When the shaft 48 is moved to the left upon stopping the machine, the arm 178 is moved out of engagement with the pin on the member 177 and said member is moved by a spring 179 beneath the enlargement at the end of the arm 176, thereby preventing the spring 175 from actuating the member 173 to lock the welt guide and work rest slides. 80 85 90 95

The welt guide is provided with a rearwardly extending projection 180 to which is adjustably secured a plate 181, the end of which is upturned in position to engage the hub of the arm 146 and thereby limit the forward movement of the welt guide when no work is in the machine. The adjustment between the plate 181 and the projection 180 is provided for by forming slots in the projection 180 and securing the plate to said projection by screws 182 passing through the slots and screwed into the plate. 100 105

In order that the welt guide may be retracted to the rear of its normal retracted position when the needle is brought to rest to permit the ready removal of the shoe and the insertion of another shoe in the machine, a laterally extending plate 183 is secured to the projection 180 on the welt guide slide and a lug 184 is formed on the lever 144 and arranged to engage the forward edge of the plate 183. During the normal operation of the machine the lug 184 is out of position to engage the plate 183 during the advancing and retracting movements of the welt guide. When however, the toggle 144-147 is broken to release the tension on the thread upon stopping the machine, the movement of the lever 144 brings the lug 184 into engagement with the plate 183 and the welt guide is thereby retracted to the rear of its normal retracted position. 110 115 120 125

Although the invention has been illustrated and described as embodied in a curved 130

- hook needle sewing machine for sewing the inseams of boots and shoes, it is to be understood that except as defined in the claims, the invention is not limited to any particular machine or type of machine. It is also to be understood that except as defined in the claims, the invention is not limited to any particular construction or arrangement of parts.
- Having explained the nature and object of the invention and having described the preferred embodiment thereof, what is claimed is:
1. A chain stitch shoe sewing machine having, in combination, stitch forming devices including a hook needle and a looper, and mechanism to cause the needle to retract while its hook is empty and come to rest out of engagement with the work during a forward cycle of movement of the machine.
  2. A chain stitch shoe sewing machine having, in combination, stitch forming devices including a hook needle and a looper, a main shaft from which said devices are operated, and mechanism to cause the needle to retract while its hook is empty and come to rest out of engagement with the work during the forward rotation of the shaft.
  3. A chain stitch shoe sewing machine having, in combination, stitch forming devices including a hook needle and a looper, and mechanism to cause the needle to retract while its hook is empty and come to rest out of engagement with the work during a forward cycle of movement of the needle.
  4. A chain stitch shoe sewing machine having, in combination, stitch forming devices including a hook needle and a looper, and mechanism acting automatically when brought into action to cause the needle to retract while its hook is empty and come to rest out of engagement with the work during a forward cycle of movement of the machine.
  5. A chain stitch shoe sewing machine having, in combination, stitch forming devices including a hook needle and a looper, and mechanism under the control of the operator and acting automatically when thrown into action to cause the needle to retract while its hook is empty and come to rest out of engagement with the work during a forward cycle of movement of the machine.
  6. A chain-stitch sewing machine, having, in combination, stitch forming devices including a hook needle and a looper, a cam shaft and mechanism to render the looper inactive during the forward rotation of the cam shaft.
  7. A chain-stitch sewing machine, having, in combination, stitch forming devices including a hook needle and a looper, a cam shaft and mechanism to render the looper inactive and to cause the needle to retract and come to rest out of engagement with the work during the forward rotation of the cam shaft.
  8. A shoe sewing machine having, in combination, stitch forming devices including a needle, a cam shaft from which said devices are operated, and means acting automatically upon stopping the machine to cause the needle to come to rest in retracted position out of engagement with the work during the continued rotation of the shaft.
  9. A shoe sewing machine having, in combination, stitch forming devices including a needle, a main shaft, devices for actuating the needle from the shaft, and means acting automatically upon stopping the machine to disconnect the needle from its actuating devices during the rotation of the shaft.
  10. A shoe sewing machine having, in combination, stitch forming devices including a needle, a main shaft, devices for actuating the needle from the shaft, and means acting automatically upon stopping the machine to disconnect the needle from its actuating devices at a predetermined point in the rotation of the shaft.
  11. A shoe sewing machine having, in combination, stitch forming devices including a needle, a cam shaft, devices for actuating the needle from the cam shaft, and means including a timing cam for disconnecting the needle from its actuating devices during the rotation of the shaft.
  12. A shoe sewing machine having, in combination, stitch forming devices including a needle, a cam shaft, devices for actuating the needle from the cam shaft, and means including a disconnecting cam and a timing cam to disconnect the needle from its actuating devices during the rotation of the shaft.
  13. A chain stitch shoe sewing machine having, in combination, stitch forming devices including a hook needle and a looper, devices for actuating the looper, and means to disconnect the looper from its actuating devices during a cycle of operations.
  14. A chain stitch shoe sewing machine having, in combination, stitch forming devices including a hook needle and a looper, a main shaft, devices to actuate the looper from the shaft, and means including a timing cam to disconnect the looper from its actuating devices during a cycle of operations before the needle is looped.
  15. A chain stitch shoe sewing machine having, in combination, stitch forming devices including a hook needle and a looper, a main shaft, devices to actuate the looper from the shaft, and means including a disconnecting cam and a timing cam to disconnect the looper from its actuating devices during a cycle of operations before the needle is looped.
  16. A chain stitch shoe sewing machine

- having, in combination, stitch forming devices, feeding devices, a main shaft, means for actuating the feeding devices from the shaft, and means operative only upon stopping the machine acting automatically to interrupt the feeding action of the feeding devices during a cycle of operations. 5
17. A chain stitch shoe sewing machine having, in combination, stitch forming devices, feeding devices and means to interrupt the feeding action of the feeding devices during a cycle of operations of the machine when they are in retracted position ready to begin a work feeding stroke. 10
18. A chain stitch shoe sewing machine having, in combination, stitch forming devices, a feed slide, a main shaft, means for actuating the feed slide from the shaft, and means acting automatically to disconnect the feed slide from its actuating means during the forward rotation of the shaft. 15
19. A chain stitch shoe sewing machine having, in combination, stitch forming devices including a hook needle and a looper, feeding devices, a main shaft, means to cause the needle to retract while its hook is empty and come to rest out of engagement with the work during the forward rotation of the shaft, and means to interrupt the feeding action of the feeding devices when the needle is brought to rest. 20
20. A chain stitch shoe sewing machine having, in combination, a hook needle and a looper, and means including a timing cam 35 to render the looper inactive during a cycle of operations before the needle is looped and thereafter to cause the needle to come to rest out of engagement with the work.
21. A chain stitch shoe sewing machine having, in combination, stitch forming devices including a hook needle and a looper, a main shaft, devices to actuate the looper from the shaft, devices to actuate the needle from the shaft, and means to disconnect the looper from its actuating devices during a cycle of operations before the needle is looped and thereafter to disconnect the needle from its actuating devices when it is in retracted position out of engagement with the work. 40
22. A chain stitch shoe sewing machine having, in combination, stitch forming devices including a hook needle and a looper, means for actuating the needle from the shaft, means for actuating the looper from the shaft, and means including a timing cam to disconnect the looper from its actuating means during a cycle of operations before the needle is looped and thereafter to disconnect the needle from its actuating means when it is in retracted position out of engagement with the work. 45
23. A chain stitch shoe sewing machine having, in combination, stitch forming devices including a hook needle and a looper, 55
- feeding devices and means acting successively to render the looper inactive and throw the feeding devices out of action and to bring the needle to rest during the forward rotation of the shaft. 70
24. A chain stitch shoe sewing machine having, in combination, stitch forming devices including a hook needle and a looper, feeding devices and means acting during a cycle of operations to render the looper inactive before the needle is looped and throw the feeding devices out of action and to bring the needle to rest in retracted position out of engagement with the work. 75
25. A chain stitch shoe sewing machine having, in combination, stitch forming devices including a hook needle and a looper, feeding devices and means including a timing cam acting during a cycle of operations to render the looper inactive before the needle is looped and throw the feeding devices out of action and to bring the needle to rest in retracted position out of engagement with the work. 80
26. A chain stitch shoe sewing machine having, in combination, stitch forming devices including a hook needle and a looper, a main shaft means to throw the needle and looper out of action during the continued rotation of the shaft, and means to throw the needle and looper into action in their proper timed relations. 85
27. A chain stitch shoe sewing machine having, in combination, stitch forming devices including a hook needle and a looper, means to throw the needle and looper out of action during the continued rotation of the shaft, and means including a timing cam to throw the needle and looper into action in their proper timed relations. 90
28. A chain stitch shoe sewing machine having, in combination, stitch forming devices including a hook needle and a looper, a main shaft, devices for actuating the needle and looper from the shaft, means to disconnect the needle and looper from their actuating devices at predetermined points in the rotation of the shaft, and means to connect the looper and needle with their actuating devices at the same points in the 100 rotation of the shaft at which they were disconnected so that they are restored to their proper timed relations. 105
29. A chain stitch shoe sewing machine having, in combination, stitch forming devices including a hook needle and a looper, feeding devices, means acting successively to throw the looper, feeding devices and needle out of action during the forward rotation of the shaft, and means to restore 110 the needle, looper and feeding devices to action in their proper timed relations. 115
30. A chain stitch shoe sewing machine having, in combination, stitch forming devices including a hook needle, a looper, feed- 120
- 65 vices including a hook needle and a looper, 125

ing devices, means to throw the looper, needle and feeding devices out of action during the forward rotation of the shaft, and means including a timing cam to restore the needle, 5 feeding devices and looper to action in their proper timed relations.

31. A chain stitch shoe sewing machine having, in combination, stitch forming devices including a hook needle and a looper, 10 means acting during a cycle of operations to render the looper inactive before the needle is looped and thereafter to cause the needle to come to rest out of engagement with the work, and means to restore the needle and 15 looper to action in their proper timed relations.

32. A chain stitch shoe sewing machine having, in combination, stitch forming devices including a hook needle and a looper, 20 feeding devices, means acting successively during a forward cycle of movement of the machine to render the looper inactive before the needle is looped and throw the feeding devices out of action and to cause the needle 25 to come to rest out of engagement with the work, and means to restore the looper, feeding devices and needle to action in their proper timed relations.

33. A shoe sewing machine having, in 30 combination, stitch forming devices including a needle, actuating devices for the needle comprising a two part cam lever, a slide for connecting the parts of said lever so that they oscillate in unison, and automatically 35 acting means for actuating the slide to connect and disconnect the parts of said lever.

34. A shoe sewing machine, having in 40 combination, stitch forming devices including a needle, a cam actuated lever for operating the needle comprising independently movable members one of which is cam actuated, a connection between the other of said members and the needle, spaced lugs formed on one of said members, a slide carried by the other of said members arranged 45 to engage between said lugs to connect said members so that they oscillate in unison, and automatically acting means for actuating the slide to connect and disconnect said 50 members.

35. A chain stitch shoe sewing machine having, in combination, stitch forming devices including a hook needle and a looper, mechanism for actuating the looper in a 55 plane substantially parallel to the plane of the needle, mechanism for actuating the looper in a plane substantially perpendicular to the plane of the needle, and means to render one of said mechanisms inoperative 60 so that the looper is actuated in a single plane only.

36. A chain stitch shoe sewing machine having, in combination, stitch forming devices including a hook needle and a looper 65 mechanism for actuating the looper com-

prising a slide mounted to reciprocate in a plane parallel to that of the needle, an arm pivotally mounted on the forward end of the slide to oscillate in a plane at right angles to the plane of the needle and having 70 its ends projecting above and below the slide, means for securing the looper in the lower end of the arm, a rock shaft arranged parallel to the slide, an arm at the forward end of the rock shaft, connecting mechanism between the arm on the rock shaft and the upper end of the looper carrying arm arranged to be thrown into and out of connection with the arm on the rock shaft, and means to throw said mechanism into and out 80 of connection with the arm on the rock shaft.

37. A chain stitch shoe sewing machine having, in combination, stitch forming devices including a curved hook needle and a looper, mechanism for actuating the looper 85 in a plane parallel with the plane of the needle, a rock shaft for actuating the looper in a plane perpendicular to the plane of the needle, an arm secured to the forward end of said rock shaft, a pin mounted on 90 said arm, a second arm loosely mounted on said rock shaft and arranged to slide longitudinally thereof and provided with a perforation to receive said pin, means to connect said last arm with the looper, means to 95 move said last arm longitudinally of the rock shaft to engage said pin in and disengage it from the perforation in said arm to throw the looper into and out of operative connection with the rock shaft. 100

38. A shoe sewing machine, having in combination, stitch forming devices, a feed slide, a lever for actuating the slide, a cam roll mounted on the lever, a cam for engaging the roll to actuate the lever, and means 105 to move the lever to engage and disengage said cam roll and said cam to throw the feed slide into and out of action.

39. A shoe sewing machine, having in combination, stitch forming devices, a feed 110 slide, an oscillating cam lever for actuating the feed slide comprising pivotally connected members, a connection between one of said members and the feed slide, a cam roll mounted on the other of said members, a cam for engaging said cam roll to oscillate the cam lever, and means to actuate said last member to engage and disengage said cam roll and said cam to throw the feed slide into and out of action. 115

40. A chain stitch shoe sewing machine having, in combination, stitch forming devices including a curved hook needle and a looper, means to impart movements to the looper in intersecting planes to carry the thread about the needle, and mechanism for causing the looper to operate in a single 125 plane only thereby to render the looper inactive.

41. A shoe sewing machine, having, in 130

combination, stitch forming devices, a main shaft from which said devices are operated, a tension device and mechanism actuated by the forward rotation of the shaft to actuate the tension device to release the tension upon the completion of the seam.

42. A chain stitch shoe sewing machine, having, in combination, stitch forming devices, including a curved hook needle and a looper, a main shaft mechanism to cause the needle to retract while its hook is empty and come to rest out of engagement with the work, a tension device and means operated by the forward rotation of the shaft to actuate the tension device to release the tension as the needle is brought to rest.

43. A chain stitch inseam shoe sewing machine, having, in combination, stitch forming devices including a curved hook needle and a looper, a main shaft from which said devices are actuated, a welt guide, a work rest, welt guide and work rest slides, means to lock and unlock said slides, means to cause the needle to retract while its hook is empty and come to rest out of engagement with the work during the forward rotation of the shaft, and means to prevent the locking of the welt guide and work rest slides while the needle is at rest.

44. A chain stitch inseam shoe sewing machine, having, in combination, stitch forming devices including a curved hook needle and a looper, a main shaft from which said devices are actuated, a welt guide, a work rest, welt guide and work rest slides, means to lock and unlock said slides, a tension device, means to cause the needle to retract while its hook is empty and come to rest out of engagement with the work during the forward rotation of the shaft, means to prevent the locking of the welt guide and work rest slides while the needle is at rest, and means to retract the welt guide to the rear of its normal retracted position and to actuate the tension device to release the tension as the needle is brought to rest.

45. A shoe sewing machine, having, in combination, stitch forming devices, a drive shaft from which said devices are actuated, mechanism for actuating said devices from the shaft, means to disconnect certain of said devices from their actuating mechanisms during the rotation of the shaft and for restoring them to connection with their actuating mechanisms so that they operate in their proper timed relations comprising a stopping cam mounted on said shaft, a starting cam mounted on said shaft adjacent the stopping cam, a lever provided with a cam roll arranged to engage alternatively the stopping and starting cams, means to actuate said lever to engage the roll thereon with the stopping cam upon movement of the treadle to disconnect the machine from the source of power and to engage the roll on

said lever with the starting cam when the treadle is moved to start the machine.

46. A chain stitch sewing machine, having, in combination, a cam shaft, stitch forming devices including a hook needle and a looper operated from the cam shaft, and means acting automatically upon stopping the machine to interrupt the looping during the forward rotation of the cam shaft action of the looper and bring the needle to rest out of engagement with the work while its hook is empty.

47. A chain stitch sewing machine, having, in combination, stitch forming devices including a hook needle and a looper, and means acting automatically upon stopping the machine to free the last needle loop from the stitch forming devices and bring the needle to rest out of engagement with the work without reversing the cycle of operations.

48. A shoe sewing machine, having, in combination, stitch forming devices, means to cause the needle to retract while its hook is empty and come to rest while out of engagement with the work during the forward rotation of the shaft, means to throw the feeding devices out of operation as the needle is brought to rest, means to throw the feeding devices into action in timed relation to the needle and other parts of the machine after the needle has started to advance in the first cycle of stitch forming operations upon starting the machine.

49. A chain stitch sewing machine, having, in combination, stitch forming devices including a hook needle and a looper, and means acting automatically upon stopping the machine to interrupt the looping action of the looper during the continued operation of the needle, and bring the needle to rest out of engagement with the work while its hook is empty.

50. A chain stitch sewing machine, having, in combination, stitch forming devices including a hook needle and a looper, and means acting automatically upon stopping the machine to interrupt the normal cycle of operations by preventing the looper from laying the thread in the hook of the needle, and to bring the needle to rest when it has retracted out of engagement with the work with its hook empty at the end of the cycle.

51. A shoe sewing machine having, in combination, stitch forming devices, including a hooked needle and a looper and mechanism to interrupt the action of the looper during a cycle of operations.

52. A shoe sewing machine having, in combination, stitch forming devices, including a needle, a cam shaft from which said devices are operated and automatically operating mechanism to disconnect the needle from the shaft and to cause the needle to come to rest in retracted position out of en-

gagement with the work during the continued rotation of the shaft.

53. A shoe sewing machine having, in combination, stitch forming devices, including a needle, a cam shaft, means for actuating the needle from the shaft and automatically operating mechanism for disconnecting the needle from its actuating means.

54. A shoe sewing machine having, in combination, stitch forming devices, including a needle, a main shaft, means for actuating the needle from the shaft and automatically operating mechanism for disconnecting the needle from its actuating means at a 15 predetermined point in the rotation of the shaft.

55. A chain stitch shoe sewing machine having, in combination, stitch forming devices, including a hooked needle and a 20 looper, means to actuate the looper and mechanism including a timing cam to disconnect the looper from its actuating means during a cycle of operations.

56. A shoe sewing machine having, in combination, stitch forming devices, including a hooked needle and a looper, feeding devices, a main shaft, means to cause the needle to retract while its hook is empty and come to rest out of engagement during 25 the forward rotation of the shaft and means to interrupt the feeding action of the feeding devices.

57. A shoe sewing machine having, in combination, stitch forming devices, including a hooked needle and a looper, feeding 35 devices, a main shaft and means for rendering the looper and feeding devices inactive during the forward rotation of the shaft.

58. A shoe sewing machine having, in combination, stitch forming devices, including a hooked needle and a looper, feeding 40 devices, a main shaft, means for rendering the looper and feeding devices inactive during the forward rotation of the shaft and for arresting the operation of the needle. 45

59. A shoe sewing machine having, in combination, stitch forming devices, including a hooked needle and a looper, a main shaft, means for rendering the looper inactive during the forward rotation of the 50 shaft and for arresting the operation of the needle.

60. A shoe sewing machine having, in combination, stitch forming devices, including a needle, feeding devices, a cam shaft, 55 means acting automatically to interrupt the feeding action of the feeding devices and to arrest the operation of the needle during the rotation of the shaft.

ERASTUS E. WINKLEY.

Copies of this patent may be obtained for five cents each, by addressing the "Commissioner of Patents,
Washington, D. C."

It is hereby certified that in Letters Patent No. 1,197,988, granted September 12, 1916, upon the application of Erastus E. Winkley, of Lynn, Massachusetts, for an improvement in "Sewing-Machines," an error appears in the printed specification requiring correction as follows: Page 13, claim 46, strike out lines 74-75 and insert the words *action of the looper during the forward rotation of the cam shaft and bring the*; and that the said Letters Patent should be read with this correction therein that the same may conform to the record of the case in the Patent Office.

Signed and sealed this 31st day of October, A. D., 1916.

[SEAL.]

Cl. 112—20.

R. F. WHITEHEAD,

Acting Commissioner of Patents.
